STAIRCASE RAILING

George Hadley, Fourth Ave., Victory Lakes, Cecil, N.J.

Filed Feb. 27, 1962, Ser. No. 69,049

Term of patent 14 years

(Cl. D13—7)

FIGURE 1 is a front elevational view of a staircase railing showing my new design; and

FIGURE 2 is a front end view of the staircase railing and FIGURE 3 is a top edge view of the staircase railing.

The dominant features of my design reside in the portions shown in full lines. The staircase and posts have been shown in several views for illustrative purposes only.

I claim:

The ornamental design for a staircase railing, substantially as shown and described.
